[57] ABSTRACT

A stack closure for closing the exhaust end of an exhaust stack to prevent the exhaust of gases from the stack and for opening the exhaust end when desired. A pivotable support frame is connected to a base member located at the exhaust end. A cap is connected to the frame by a floating connection for providing random movement between the cap and the frame. The frame pivots to move the cap into and out of closing engagement with the base and the floating connection permits self-alignment of the cap with the base during closing. Resilient stabilizing members act to stabilize the random movement between the cap and the frame. A seal member seals the cap and base, and pressure limiters protect the seal member from excessive pressure exerted thereon when the cap is in sealing engagement with the base.

CLOSURE FOR EXHAUST STACK

BACKGROUND OF THE INVENTION

1. Field of the Invention

The present invention relates generally to ventilation and specifically a valved cap for chimneys.

2. Description of the Prior Art

Recently, attention has been focused on serious air pollution problems particularly occurring in industrialized areas. Industrial wastes such as exhaust gases are normally discharged into the atmosphere. As a result, effective means used to rid the atmosphere of pollutants in exhaust gases have become increasingly important.

One such effective means is the electrostatic precipitator. When precipitators are used, the normally open exhaust end of exhaust stacks must be closed to divert gases into the precipitator from their path of travel through the stack. An effective way of closing the exhaust end of a stack is by using a pivotal closure or cap which may be quickly opened to prevent a backup of the gases in certain situations such as when the precipitator becomes inoperable. It is important that the cap be capable of effectively sealing the stack for preventing the escape of gases into the atmosphere and because during the operation of the precipitator the closed stack is, in effect, merely a piece of ductwork in the gas cleaning system and as such is at times required to be under a negative or positive pressure.

Such an exhaust stack closure is shown in Snader U.S. Pat. No. 3,545,365 including a counterweighted frame and a closure cap having the size and shape of the exhaust end of a stack. The frame is pivotally mounted to a base attached to the top of the stack for sealing engagement with the closure cap. Such caps are capable of doing an effective job only when they properly engage the base to form an effective seal therewith. The cap is rigidly attached to the pivotal frame and occasionally a cap is installed which fails to effectively seal the stack due to slight offsets or vibrations in alignment between the cap and base which may occur during manufacture or installation. For example, the cap is welded to the frame and at times the cap becomes canted slightly out of alignment with the top of the stack. As a result, an effective seal is not made since the rigidly connected cap is not able to conform in alignment with the base and only a portion of the cap and base may be engaged whereas a diametrically opposed portion thereof may not even make contact due to the rigidity of the cap and frame attachment. Resilient material, placed between the cap and base to aid in sealing, is sometimes damaged or even cut by uneven pressure resulting from attempting to positively close the misaligned cap.

It can be seen from the foregoing that it would be advantageous to provide a reliable cap having the ability to accommodate variations in alignment between the cap and base and thereby automatically self-align itself with the base to form an effective closure therewith. Also, there is a need for a resilient seal member to seal the cap and base which is not subject to damage due to uneven pressure resulting from a misaligned cap.

SUMMARY OF THE INVENTION

Accordingly, the present invention provides a reliable cap capable of accommodating variations in alignment between the cap and base and thereby aligning

with the base to form an effective closure therewith. This is accomplished by the use of a floating connection between the cap and frame for permitting relative multi-directional or random movement therebetween rather than the conventional rigid connection. Resilient stabilizers aid in stabilizing the relative multi-directional movement. Also, the stack closure of the present invention has improved sealing capabilities due to the use of a resilient seal member provided between the base member and the cap. Preferably, the seal is made from closed cell silicone sponge rubber. The seal member is not subjected to uneven pressure between the base and cap due to the alignment capabilities of the cap and also due to pressure limiters for limiting excessive pressure on the seal member and for maintaining substantially equal pressure between the cap and the seal member.

The above and other novel features of the invention will appear more fully from the following drawings, the detailed description and the claims. The drawings are not intended as a definition of the invention but are for the purpose of illustration only.

DRAWINGS

In the drawings wherein like parts are marked alike: FIG. 1 is a segmented partial side elevation of an exhaust stack including a closure with power means for operating the closure;

FIG. 2 is a plan view of the closure of FIG. 1;

FIG. 3 illustrates a segment of the closure in side elevation and further illustrates the cap in closing engagement with the base;

FIG. 4 illustrates a segment of the closure of FIG. 3 and further illustrates the cap out of closing engagement with the base;

FIG. 5 illustrates the possible relative multi-directional movement between the plates of the floating connection;

FIG. 6 illustrates an enlarged segmented view of one of the resilient stabilizing members connected to the frame and the cap; and

FIG. 7 illustrates an enlarged segmented view of one of the pressure limiters and its effect on the engagement of the cap and the seal member.

DESCRIPTION OF THE PREFERRED EMBODIMENT

A stack closure generally designated 10 is shown adjacent the exhaust end 12 of an exhaust stack 14, FIG.

1. Closure 10 includes a base 20; a frame 30 pivotally connected to base 20; a cap 40 attached to frame 30 by a floating connection generally designated 50; and means for pivoting frame 30 so as to move cap 40 into closing engagement with base 20. Floating connection 50 permits relative multi-directional movement of cap 40 with respect to frame 30. Such relative movement provides a cap 40 which is capable of accommodating variations in alignment between cap 40 and base 20 thus permitting cap 40 to automatically self-align with base 20 to form an effective closure therewith. Seal member 21, best shown in FIG. 7, seals the closure of cap 40 and base 20. Again in FIG. 1, pressure limiters 60 advantageously limit the pressure exerted on seal member 21 by cap 40 and provide substantially equal pressure therebetween around the periphery of the seal.

Resilient members 70 are preloaded in compression between frame 30 and cap 40 for stabilizing the relative movement therebetween. Pressure limiters 60 are provided at locations A, B, C and D, best shown in FIG. 2, and resilient members 70 are provided at locations E, F, G and H, also shown in FIG. 2. Frame 30 is pivotable by power means located near the base of stack 14, as viewed in FIG. 1, comprising a reversible electric motor 80 and a pair of screw jacks 81 and 82 operable for simultaneously moving cables 83 and 84 in opposite directions so as to rotate circular track lever arm 85.

Base 20, FIG. 1, comprises band 22 which encircles and is secured to the exhaust end 12 of stack 14 such as by welding. Band 22 includes upper annular flange 23 and lower annular flange 24 spaced from flange 23, better shown in FIG. 3. Flanges 23 and 24 reinforce band 22 and upper flange 23 provides an annular seat 25 upon which seal member 21 is preferably mounted. If desired, seal member 21 may be secured to cap 40.

FIGS. 3 and 7 illustrate the mating engagement of base 20 and cap 40 including seal member 21 mounted within an annular channel formed by inner ring 26 and outer ring 27 located upon annular seat 25. Seal member 21 preferably comprises a closed cell silicone resilient material such as closed cell silicone sponge rubber. The closed cell silicone material of seal member 21 is substantially non-porous and forms a positive seal between cap 40 and base 20. This is important because, during operation of precipitators, the closed stack is exposed to negative or positive pressures and therefore an effectively sealed stack is desirable.

FIG. 2 shows bearing mounts 28 and 29 secured to base 20, such as by welding. Bearing mounts 28 and 29 support bearings 101 and 102. A shaft 103 is pivotally mounted in bearings 101 and 102. These bearings are laterally spaced so that pivot shaft 103 extends between them. If desired, the bearings may comprise metal supports with round or square holes therein corresponding to the diameter of shaft 103.

Frame 30 includes a main support 31 and parallel supports 32 substantially shorter in length than support 31, see FIGS. 1 and 2. Supports 32 are axially adjacent support 31 at equally spaced distances on opposite sides thereof. Support 31 may comprise an I beam or, if desired, two channels may be welded together back to back. Supports 32 preferably comprise substantially equivalently sized channels. Counterweight 33, preferably an I beam, shown on the right in both FIGS. 1 and 2, is attached to support 31 and supports 32 preferably by welding. At an opposite end, or on the left as shown in FIG. 2, support 31 and supports 32 are connected by cross supports 34 which may be similar in cross section to supports 32.

At a predetermined point between counterweight 33 and cross supports 34, main support 31 and parallel supports 32 are attached to shaft 103. In this manner, frame 30 is pivotable about the centroidal axis of shaft 103; the shaft being pivotally mounted in bearings 101 and 102.

Counterweight 33, on the right of shaft 103, as viewed in FIGS. 1 and 2, acts to counterbalance the weight of cap 40 attached to frame 30 on the left of shaft 103. The beneficial effect of counterbalancing the weight of cap 40 is that less force is required by the power means to pivot frame 30 for either closing or opening stack 14.

Cap 40, FIG. 3, comprises a circular plate 41 having a depending peripheral flange 42. Edge 44 of flange 42 engages seal member 21 to form an effective seal therebetween. Plate 41 is generally flat and is stiffened or reinforced by a plurality of intersecting structural members 43, better shown in FIG. 2. Reinforcing members 43 may be angles or channels or the like, and are attached to plate 41 preferably by welding, or by bolts if desired, and act to reinforce or stiffen cap 40. Also, reinforcing members 43 are substantially co-planar with plate 41 and frame 30 and are extended radially outwardly from the center of cap 40 terminating shortly beyond the outer periphery thereof preferably at equally spaced intervals of at least 90° each although, if desired, more members may be placed at smaller equally spaced angular intervals. Furthermore, members 43 are important and useful in the successful functioning of the pressure limiters 60 and resilient stabilizing members 70 as will be more fully discussed herein.

Floating connection 50, FIG. 5, comprises upper plate 51; intermediate plate 52; lower plate 53; and shoulder bolts 54.

Upper plate 51 is attached to frame 30, preferably by welding, see FIG. 4. Also, when viewed in FIG. 2, it can be seen that upper plate 51 is located substantially adjacent the center of cap 40 and is intersected by structural members 31 and 34 of frame 30. In this manner, portions of plate 51, located between the intersecting members 31 and 34 attached to the plate, are exposed and provide places for bolts 54 which are not obstructed by structural members.

Lower plate 53, FIG. 4 is attached to intersecting reinforcing members 43, preferably by welding. It can be seen that lower plate 53 is located substantially adjacent upper plate 51 and therefore similarly adjacent the center of cap 40. Portions of plate 53 are located between intersecting structural members 43 and are exposed to provide places for bolts 54 which are not obstructed by structural members, such as that described for upper plate 51.

Intermediate plate 52 is firmly attached to upper plate 51, such as by welding. If desired, plate 52 could be an integral portion of plate 51 protruding therefrom.

Upper and lower plates 51 and 53 respectively, FIG. 5, being substantially aligned with one another, are provided with aligned bolt holes 55 preferably located at equally spaced intervals between the attached structural members 31 and 34 of frame 30, and reinforcing structural members 43 as previously discussed. Shoulder bolts 54, provided in holes 55, include a shoulder portion 54a which overlies holes 55 so as not to permit bolts 54 to pass through holes 55. Threaded shaft portion 54b of bolts 54 extends through aligned holes 55. Washer 56 and hex nut 57 is attached to the end of bolt 54 opposite the end having shoulder portion 54a. Washer 56 overlies holes 55 in a manner similar to that described for shoulder portion 54a. Hex nut 57 maintains washer 56 in the desired position on shaft 54b. When bolts 54 are loosely mounted in holes 55 of plates 51 and 53, and washer 56 and hex nut 57 are attached in place, plates 51 and 53 are secured together in spaced apart relationship for limited relative movement axially along the length of shaft 54b; that is, movement of plates 51 and 53 is limited by shoulder 54a and washer 56. Furthermore, the amount of limited relative movement between spaced apart plates 51 and 53 may be increased or decreased by adjusting hex nut

57 with respect to shoulder 54a. Bolts 54 are further loosely mounted since holes 55 are substantially larger in diameter than shaft 54 to permit plates 51 and 53 to have relative movement laterally and angularly with respect to each other and with respect to shaft 54b. Therefore, since plate 51 is attached to frame 30 and since plate 53 is attached to cap 40, the result is that frame 30 and cap 40 have relative multi-directional or random movement within the limits of holes 55, shoulder 54a and washer 56 thus permitting cap 40 to automatically self-align with base 20 for positive closing engagement therewith; that is, the floating type connection between cap 40 and frame 30 permits the cap to seek its own level or the level of base 20.

The maximum amount that cap 40 can be canted out of alignment with frame 30 is illustrated in FIG. 5 wherein it can be seen that plate 53 is capable of a substantial amount of misalignment with respect to plate 51. This maximum condition would probably only occur when frame 30 is pivoted to a substantially vertical position away from base 20. In the maximum misaligned position, plate 53 may contact either edge 51a of plate 51 or edge 52a of plate 52. When frame 30 is lowered toward base 20 and into a substantially horizontal position, the loosely mounted cap tends to seek its own level due to gravity, and plate 53 which is firmly attached to cap 40 will shift position with respect to plates 51 and 52. As frame 30 continues to be lowered, approaching the horizontal position for alignment with base 20, plate 53 gradually moves out of contact with edge 52a and ultimately rests upon washers 56 prior to cap 40 contacting base 20, resulting in a space of separation between plates 52 and 53 as shown in FIG. 4.

Conversely, as frame 30 is raised away from base 20 and into a substantially vertical position, the loosely mounted cap 40 continues to seek its own level and plate 53 rests on washers 56. Eventually, however, as frame 30 approaches the vertical position cap 40 will become substantially misaligned with respect to frame 30 and plate 53 will correspondingly shift position with respect to plates 51 and 52.

FIG. 5 also illustrates, through the alternate positions of plate 53 with respect to plate 51, the substantial amount of misalignment which can occur between cap 40 and base 20. For example, FIG. 4 illustrates cap 40 out of contact with base 20 as would be the case just prior to closing engagement as cap 40 is being lowered, or just after cap 40 has begun to be raised for opening. Considering, however, the possibility that base 20 can be substantially misaligned with respect to pivotal frame 30 when frame 30 is lowered into the horizontal position, the combination of the separation of plates 52 and 53 due to gravity and the substantial multi-directional misalignment which can be accommodated by floating connection 50 enables cap 40 to compensate for an appreciable amount of misalignment between frame 30 and base 20. It can be seen that cap 40 is operable for mating alignment with base 20 due to their relative multi-directional movement.

When cap 40 has engaged base 20 the cap and base are substantially aligned and are in continuous contact along edge 44 of flange 42, FIGS. 3 and 7. When such contact is made, frame 30 continues to be lowered until plate 52 contacts plate 53. Frame 30 exerts a downward force which is transferred to cap 40 when plate 52 contacts plate 53. Such downward force maintains cap 40 in closing engagement with base 20. Should mis-

alignment occur between base 20 and frame 30, a corresponding misalignment will occur between plates 52 and 53 so that the downward force will be transferred from the frame to the cap when edge 52a contacts plate 53, as best illustrated in FIG. 5.

Of course, if desired, plate 52 could be firmly attached to plate 53 instead of to plate 51, or plate 52 could have a slightly rounded configuration similar to a segment of a sphere, the main purpose being to provide a localized point of contact between plates 51 and 53.

Pressure limiters 60, located at A, B, C and D of FIG. 2, advantageously limit pressure exerted on seal member 21 by cap 40. FIG. 3 illustrates cap 40 in closing engagement with base 20 including edge 44 in sealing contact with seal member 21. If the downward force exerted on cap 40 by frame 30 were not limited, edge 44 could continue to be forced downward to contact annular seat 25 of base 20. As a result, seal member 21 might be cut or severely damaged by edge 44. Pressure limiters 60 are secured to members 43 of cap 40 and therefore movement of the secured limiters depends on the multi-directional movement permitted by floating type connection 50 thus causing limiters 60 to move relative to cap 40. Preferably, pressure limiters 60 include bolt 61 secured to flange 43a by jam nuts 62, FIG. 7. In this manner, bolt 61, including extended portion 61a, may be extended from reinforcing member 43 to a predetermined length for engagement with a portion of base 20 such as pads 28 provided at locations A, B, C and D. Pads 28 are secured, such as by welding, to base 20 by members 29 which may comprise angles welded to upper and lower flanges 23 and 24 respectively. Since pressure limiters 60 and cap 40 are secured to reinforcing members 43 and have relative movement therewith, the contact of extended portions 61a with pads 28 will limit the pressure exerted on seal member 21 by edge 44 of cap 40 and the limiters may be adjusted to provide substantially equal pressure between the cap and the seal member along the continuous sealing contact of edge 44 and seal member 21. At least 3 limiters and pads are needed to establish a stable co-planar relationship between cap 40 and base 20. The pads and limiters are preferably located at equally radially spaced intervals with respect to cap 40.

Resilient members or stabilizers 70 are preferably located at E, F, G and H, see FIG. 2, and comprise springs 76 preloaded in compression between frame 30 and cap 40 for stabilizing the relative multi-directional movement therebetween. Such preloading maintains plates 52 and 53 out of contact when cap 40 is not in closing engagement with base 20, see FIG. 4. The amount of separation of plates 52 and 53 is limited by washers 56 and hex nuts 57 as previously described. Stabilizers 70 are preferably located at the four locations E, F, G and H, however, more than four stabilizers may be used if preferred. At least 3 stabilizers are needed to establish a stable co-planar relationship between frame 30 and cap 40 and the stabilizers should be located at equally radially spaced intervals with respect to cap 40. A beneficial effect of stabilizers 70 is that they stabilize cap 40 when in the open position to counteract fluttering of the floating cap which can be caused by high winds.

Preferably, stabilizers 70 include support plate 71 adjustably mounted by bolt 72 and slot 73 to member 31 of frame 30. Bolt 74 depends from flange 71a and is

fixedly attached thereto. Shaft portion 74a of bolt 74 is secured for limited relative movement with reinforcing member 43 by a conventional locknut 75. Resilient stabilizing spring 76 surrounds shaft portion 74a of bolt 74 between flange 71a and reinforcing member 43. Precompression of spring 76 permits limited relative movement of resilient member 43 with respect to frame 30 within the limits of shoulder bolts 74 and locknut 75 as shown in phantom outline in FIG. 6.

Power for moving pivotable frame 30 is supplied by reversible electric motor 80 located on support 80a near the base of stack 14, see FIG. 1. Screwjacks 81 and 82 are located on support 80a and are coupled to be simultaneously driven by motor 80. One of the screwjacks is a right-hand screw and the other is a left-hand screw. In this manner, when reversible motor 80 rotates in one direction the screwjacks will simultaneously move in opposite directions; that is, one screwjack will move upward while the other moves downward. Screwjacks 81 and 82 are connected to cables 83 and 84 respectively. The cables are secured to circular track lever arm 85 and the lever arm is secured to shaft 103. The cables 83 and 84 are secured respectively to left and right positions (as viewed in FIG. 1) of circular track lever arm 85 using a suitable type of securing device such as a clevis and pin 86. Therefore, when screwjacks 81 and 82 are driven by motor 80, the connected cables 83 and 84 are simultaneously moved in opposite directions thus rotating circular track lever arm 85 and shaft 103 in a clockwise direction (as viewed in FIG. 1) and pivoting the closure 10 which is secured to shaft 103 for opening stack 14. Alternately, when motor 80 is reversed, lever arm 85 is rotated counterclockwise to pivot the closure 10 for closing stack 14. Since both screwjacks 81 and 82 operate simultaneously, but in opposite directions, there is always positive control of the closure at all times during opening and during closing of stack 14. Since the closure is counterweighted, only a small torque is required to pivot closure 10 for opening and closing stack 14.

The beneficial effect of the circular track lever arm 85 can be realized from FIG. 1 wherein it can be seen that cables 83 and 84 follow circular track 85a thus providing a cable pull which is always 90 degrees to the lever arm; that is, the line of action, designated a, of cable 84 is always disposed at 90° from a radius designated r, struck from the center of lever 85 and intersecting line a at the point where cable 84 is connected to lever 85 by clevis and pin 86. This cable pull condition will exist at all points along cables 83 and 84 which are in engagement with track 85a. Therefore, engagement of cables 83 and 84 with track 85a should be maintained at the clevis and pin 86 when lever 85 is rotated to either fully open or close cap 40. In this manner, varying torque acting on shaft 103 will be minimized.

The foregoing has illustrated a novel reliable closure for exhaust stacks including a frame pivotally connected to a base, which base is secured to the exhaust end of an exhaust stack; a cap connected to the frame

by a floating connection operable to permit relative multi-directional movement between the frame and the cap thus permitting the cap to accommodate variations in alignment between the cap and the base and to thereby align with the base for closing engagement therewith; resilient stabilizing members connected to the frame and the cap so as to aid in stabilizing the relative multi-directional movement therebetween; an improved seal member to seal the closing engagement of the cap and the base; and pressure limiters for limiting excessive pressure on the seal member and for maintaining substantially equal pressure between the cap and the seal member.

Having thus described the invention in its best embodiment and mode of operation, that which is desired to be claimed by Letters Patent is:

1. A stack closure for closing the exhaust end of an exhaust stack to prevent the exhaust of gases therefrom and for opening said exhaust end to permit the exhaust of gases therefrom therefrom, closure comprising:
  - a base attached to said exhaust end;
  - a closure cap engageable with said base for closing said exhaust end;
  - a moveable support frame connected to said closure cap for moving said closure cap into and out of engagement with said base;
  - a floating connection means between said closure cap and said moveable support frame for aligning said closure cap with said base for positive closing engagement therewith;
  - a drive means for moving said support frame;
  - said floating connection means between said closure cap and said support frame including loosely mounted bolts connecting said closure cap to said support frame for permitting random movement therebetween thereby permitting said closure cap to be self-aligning with said base;
  - a plurality of resilient members preloaded in compression between said support frame and said closure cap for stabilizing said random movement therebetween;
  - a resilient seal member mounted to one of said base and said closure cap for sealing against the exhaust of gases therebetween;
  - said closure cap including reinforcing means comprising metal members rigidly attached to said closure cap in substantially co-planar relationship with said support frame; and
  - a means for limiting pressure exerted on said seal member when said closure cap is pivoted into sealing engagement with said base,
- said pressure limiting means comprising bolts extending from said reinforcing means to a predetermined length for engagement with a portion of said base, whereby engagement of said bolts with said base limits the pressure exerted on said seal member by said closure cap and provides a substantially equal pressure therebetween.
